UNITED STATES PATENT OFFICE.

GEORGE DUNHAM, OF UNIONVILLE, CONNECTICUT.

DIES AND PUNCHES FOR MAKING HEXAGONAL NUTS.

No. 843,875.

Specification of Letters Patent.

Patented Feb. 12, 1907.

Application filed February 7, 1905. Serial No. 244,572.

To all whom it may concern:

Be it known that I, GEORGE DUNHAM, a citizen of the United States, residing at Unionville, in the county of Hartford and State of Connecticut, have invented certain new and useful Improvements in Dies and Punches for Making Hexagonal Nuts, of which the following is a specification.

My invention relates to improvements in dies and punches for making hexagonal nuts; and the objects of my improvements are to facilitate the manufacture of the nuts and at the same time produce a smooth and attractive nut.

15 In the accompanying drawings, Figure 1 is a face view of the punches and their holder. Fig. 2 is an elevation of the said punches and holder as viewed from the upper side when in the position shown in Fig. 1, together with a 20 sectional view of the dies. Fig. 3 is a plan view of a bar of iron, illustrating the action of the said dies and punches.

A designates any suitable punch-holder in which to mount the several punches and by 25 means of which holder the punches may be secured in a press or nut-making machine. As shown, the several punches are secured within suitable sockets in the punch-holder A by means of set-screws 8. The round- 30 hole punch 5 is shown at the left, and the shearing, trimming, or finishing punch 6 is shown at the right, a distance from the round-hole punch equal to the width of three hexagonal blanks measured from corner to 35 corner, whereby the centers of the punches 5 and 6 represent the centers of the first and fourth of four consecutive nut-blanks. Half-way between the punches 5 and 6 is a pair of notching-punches 7, with their two substantially V-shaped sides at an angle of sixty degrees to the line from center to center of the punches 5 and 6, so as to cut out from opposite edges of the bar or stock, Fig. 3, two substantially V-shaped notches 7^a between two 40 joining nut-blanks. The several dies are formed in the die block or plate B, and as the said dies are of the same contour as the punches the face view of the punches shown in Fig. 1 also correctly represents a face view 45 of the several dies to which the said punches are fitted. The die plate or block B, in which the several dies are formed, may be fitted to and held within any ordinary die-holder. The round-hole die 5^a and the shearing or 50 finishing die 6^a are shown by full lines in Fig. 55 2, while one of the dies for one of the notch-

ing-punches is indicated in broken lines in said Fig. 2. The distance from center to center of the notching and finishing-dies is equal to half the width of the finishing-die plus a 60 given number of blanks for the said finishing-dies. As shown, it is one-half the width of the said die plus the width of one nut-blank. The opposite V-shaped dies and their punches are set so closely together that they would 65 substantially meet each other were it not for their truncated apices. By means of these truncated apices, which cut in a direction out of alignment with the inclined sides of the dies, a connecting portion is formed on the 70 bar, as shown at the right-hand end of Fig. 3, while at the same time the main portion of the said sides are on lines that would, without the said apices, substantially sever the bar.

The bar or stock, Fig. 3, is fed in from the 75 left and first operated upon by the round-hole die and punch to punch the hole 1, then fed longitudinally the width of one nut for punching the round 2 and at the same time have the notching-punches shear off the two 80 front corners of the bar, as shown at the right-hand end of the bar in Fig. 3. At the next forward feed and action of the dies and punches the round hole 3 and the pair of notches 7^a are cut, thereby nearly completing 85 the blanking of a hexagonal nut of which the round hole is the center, but leaving a neck 9 with sufficient stock between the said two notches to hold the end blank on the bar for moving said blank along to the action of 90 the final die. At the next feed and action of the dies and punches another round hole is punched, another pair of notches formed, while the shearing or finishing die and punch completely severs the blank of which the 95 hole 1 is the center. The blank so cut off was before severing so nearly the form of a hexagonal nut that only a thin shaving has 100 to be trimmed or sheared off from its sides, and the neck is so small that it cuts off readily and smoothly.

It is apparent that some changes from the specific construction herein disclosed may be made, and therefore I do not wish to be understood as limiting myself to the precise 105 form of construction shown and described, but desire the liberty to make such changes in working my invention as may fairly come within the spirit and scope of the same.

I claim as my invention--

110 1. In a set of dies and punches for making hexagonal nuts, the combination of a finish-

ing or blanking die of a hexagonal form in plan view, with a punch of corresponding form, a pair of notching-dies of substantially a V form in plan view, the same being arranged in pairs with the apices of the V's extended inwardly from opposite directions with their inclined sides at an angle corresponding with the sides of the said finishing or blanking die, a pair of notching-punches of a form corresponding with that of the said notching-dies, a connecting-plate for maintaining the said dies in their relation to each other, and a punch-holder for maintaining the said punches in their relation to each other, the said dies and punches being located in their relation to each other with the centers of the notching and blanking dies a distance from each other equal to one-half the width of the said blanking-die, plus the width of a given number of nut-blanks.

2. In dies and punches for making hexagonal nuts, the combination of a finishing or blanking die of a hexagonal form in plan view with a punch of corresponding form, a pair of notching-dies and coacting punches in the form of an acute-angled V with a truncated apex, the said dies being set so as to substantially meet at their points were it not for the said truncated apices, a connecting-plate for maintaining the said dies in their relation to each other, and a punch-holder for maintaining the said punches in

their relation to each other, the said dies and punches being located with the centers of the notching and blanking dies a distance from each other equal to one-half the width of said blanking-die, plus the width of a given number of nut-blanks.

3. In dies and punches for making hexagonal nuts, the combination of a finishing or blanking die of a hexagonal form in plan view with a punch of corresponding form, a pair of notching-dies and coacting punches in the form of an acute-angled V with a truncated apex, the said dies being arranged together for notching the opposite edges of a bar of metal on lines corresponding with the confronting sides of two adjoining nut-blanks and with the said truncated apices at the bottom of each notch, a connecting-plate for maintaining the said dies in their relation to each other, and a punch-holder for maintaining the said punches in their relation to each other, the said dies and punches being located with the centers of the notching and blanking dies a distance from each other equal to one-half the width of said blanking-die, plus the width of a given number of nut-blanks.

GEORGE DUNHAM.
